UNITED STATES PATENT OFFICE.

FRANK A. BARNHART, OF CHAMBERSBURG, PENNSYLVANIA.

DESIGN FOR A MUD-GUARD FOR BICYCLES.

SPECIFICATION forming part of Design No. 27,179, dated June 8, 1897.

Application filed April 26, 1897. Serial No. 634,046. Term of patent 7 years.

To all whom it may concern:

Be it known that I, FRANK A. BARNHART, a citizen of the United States, residing at Chambersburg, in the county of Franklin and State of Pennsylvania, have invented and produced a certain new and original Design for Mud-Guards for Bicycles; and I do declare the following to be a full, clear, and exact description of the invention, such as will enable others skilled in the art to which it appertains to make and use the same.

My invention relates to a new and useful design for a mud-guard for bicycles; and it consists of a device of the configuration and ornamentation shown in the accompanying drawing, in which I have illustrated my invention in perspective.

The leading features of my design consist in a crescent-shaped plate 1, annularly con-

caved, and two rods or arms extending forwardly from said plate and provided with U-shaped ends. A mud-guard of this peculiar shape will be found to be very useful when attached to a bicycle and will prevent mud and other foreign matter being thrown up against the back of the rider by the centrifugal force of the wheel.

Having thus described my design, what I claim as new and useful, and desire to secure by Letters Patent of the United States, is—

The design for a mud-guard for bicycles, as herein shown and described.

In testimony whereof I hereunto affix my signature in presence of two witnesses.

FRANK A. BARNHART.
